UNITED STATES PATENT OFFICE.

HERBERT M. STURGIS, OF KANSAS CITY, MISSOURI.

BRUSH.

SPECIFICATION forming part of Letters Patent No. 663,246, dated December 4, 1900.

Application filed April 23, 1900. Serial No. 14,002. (No model.)

To all whom it may concern:

Be it known that I, HERBERT M. STURGIS, of Kansas City, Jackson county, State of Missouri, have invented certain new and useful 5 Improvements in Brushes, of which the following is a full, clear, and exact description, reference being had to the accompanying drawings, forming a part hereof.

This invention relates to brushes; and it 10 consists of the novel construction, combination, and arrangement of parts hereinafter shown, described, and claimed.

Figure 1 is a plan view. Fig. 2 is a sectional view taken approximately on the line 15 $a-a$ of Fig. 1. Fig. 3 is view showing the spraying-tube.

In carrying out this invention I provide an annular brush-block 1, integral with one side of which or rigidly secured to it is a handle 2. 20 3 denotes a T-casting, integral with which is a flange 4, the said flange being adapted to fit upon the upper surface of the brush-block, in which position it is secured by means of screws 5, thereby holding the said T-casting 25 rigidly in position. Projecting into the vertical portion of the T-casting 3 is a tubular connection 6, the said tubular connection being provided near its upper extremity with an aperture 7, the said aperture registering 30 with the horizontal portion of the tubular casting 3. The upper extremity of the tubular member 6 is interiorly screw-threaded and is retained in position by means of a thumb-screw 8, provided for that purpose. Rigidly

connected to the lower portion of the casting 35 6 is a spraying-tube 9, the said spraying-tube being annular in shape and being adapted to encircle the entire number of brush-splints, the opposite ends of said spraying-tube leading from diametrically opposite sides of the 40 casting 6. Through the inner side of the said spraying-tube is a plurality of apertures 10, the said apertures being radially arranged for the purpose of deflecting the water through the entire number of brush-splints. 45

I claim—

1. A device of the class described, comprising a brush-block, a handle integral with said brush-block, a tubular casting carried by said brush-block, a second casting removably carried by said tubular casting, and a spraying device carried by the second-mentioned casting, substantially as specified. 50

2. The herein-described brush, comprising a brush-block, a handle integral with said brush-block, a tubular casting rigidly carried by said brush-block, a second casting removably carried by the first-mentioned casting, and a spraying-tube carried by the said second-mentioned casting, the said spraying-tube encircling the entire number of brush-splints, substantially as specified. 55 60

In testimony whereof I affix my signature in presence of two witnesses.

HERBERT M. STURGIS.
